UNITED STATES PATENT OFFICE

CLARENCE MURPHY, OF BRIDGEPORT, CONNECTICUT

SPRING CLIP FOR BELTS, GARTERS, AND THE LIKE

Application filed October 14, 1926. Serial No. 141,513.

The present invention relates to improvements in spring clips for belts, supporters and the like, and is particularly adapted for attachment on a belt for engagement with a buckle, or loop of a belt, and likewise may be used as a hook for connecting two end portions of a belt together.

The clip is further adapted for use as a connector for attaching the returned end portions of a belt to the main body portion. Another and important use for the clip is as a connector and slide whereby a buckle may be attached in a manner to provide adjustment for the belt so that it may be lengthened or shortened, in fact the clip may comprise all the trimmings on a belt.

With the above and other objects in view, the embodiments of the invention are shown in the accompanying drawings. These embodiments will be hereinafter more fully described with reference thereto, and the invention will finally be pointed out in the claims.

In the drawings:—

Fig. 1 shows a front elevation of the connecting end portions of a belt, having a buckle attached, and provided with two of my improved clips;

Fig. 2 is a further front elevation of the two connecting end portions of a belt and attached buckle and provided with two of my improved clips;

Figs. 3 and 4 show a front and top edge view respectively of the connected end portions of a belt, provided with my improved clips used for connecting the two said end portions of the belt together;

Fig. 5 shows an inverted perspective view of a buckle having a web attached thereto by means of one of my improved clips;

Fig. 6 shows a central longitudinal sectional view of a buckle and attached web illustrated in Fig. 5, and one of my improved clips positioned in the buckle for engagement therewith;

Fig. 7 is a similar longitudinal sectional view with the lever of the buckle closed down to lock the clip to the buckle; and

Fig. 8 shows a buckle in front elevation attached to a belt and the free end of the

belt secured to the buckle by means of one of my improved clips, said parts substantially agreeing with the construction shown in Figs. 5, 6, and 7.

Similar reference characters indicate corresponding parts throughout the several figures of the drawing.

Referring to the drawings, the buckle employed is one of the well known commercial type, and in the embodiment illustrated comprises a shell 20 having flanges 21 along its longitudinal side edge and provided intermediate of its ends with pintle supporting ears 22. A transverse pintle 24 is supported in the ears 22 and a lever member 23 having right angular bent side flanges 25, is rotatably supported on said pintle. The lever also carries a short gripping member 28 of inverted U-shape in cross section, this gripping member is held against movement relatively to the lever member, but is adapted to be rotated therewith. The lever member 23 includes a transverse bar 26 around which the buckle end of the web or belt 35 is fastened by means of my improved clip 38.

The simpler form of the invention is shown in Figs. 1, 2, and 5 wherein it is shown as a fastening means for attaching a buckle or ring to a belt. In these instances it will be seen that the main member of the clip is formed of a single piece of wire bent into substantially the shape of a figure 8, with the wires disposed to form a straight outer bar *a*, loops *b*, *c*, *d*, and *e*, and an inner bar 27 formed of the wire end portions. These ends may be covered with a ferrule or can be disposed to form projections *i* for engagement with a buckle as shown in Figs. 1, 6 and 7. A ring 40 is pivotally connected to one of the said bars, as shown, to form a finger piece in the same manner as the section figure 8 member is used as shown in Fig. 3. In the formation of the clip the intermediate O G bars are made to cross each other several times as at *f*, *g*, and *h*, the tension of the wire being such as to cause the two elongated members to engage each other at the three places where the wires cross each other so that when the web is

threaded therebetween, ample friction is 100

provided to hold the web against slipping, see Fig. 5.

The clip which I have generally designated as 38, may be employed as a finger piece for attaching the buckle to the belt, see Figs. 1, 5, 6, and 7, by first threading the end portion of the belt through beneath outer bar *a* of the clip, then over the bar 26 of the buckle lever and then around and between the crossed and curved intermediate bars and returned in position to be clamped between the outer belt member and the inner bar portion 27 of the clip, see Fig. 5. When secured to the free end of a belt as seen in Figs. 1 and 8, it can also be used for detachably connecting said free end to a buckle by inserting the attached clip into the buckle and beneath the short arm 28 of the lever when the latter is swung to its open position as shown in Fig. 6, after which the lever is closed behind the upwardly deflected abutting end portions *i* of the bar 27 of the clip as shown in Fig. 7. In this connection the ring 40, constitutes a finger piece, and is enclosed within the loop portion 32 of the belt, which is made adjustable by means of a slide 41, see Fig. 1.

In Fig. 2, I have also shown a ring 54 secured to the clip by means of a ferrule 30 which provides for the use of my invention in connection with wider belts 57.

In Figs. 3 and 4, I have shown two of the clips secured together by a ferrule 31 and attached to a belt in which case one clip 35 serves as a finger piece within the loop 36 of the belt 35^a, while the other section or clip member is projected and directly engages the loop 37 in the connected end of the belt. This engagement is effected by simply hooking that portion of the clip comprising the loop *b* and bar *a* down into the loop 37 of the belt in a manner to frictionally engage the front member thereof between the two crossed members of the clip.

Having thus described my invention what I claim and desire by Letters Patent is:

1. A fastening clip for use upon belts and the like, comprising a wire bent into substantially the form of a figure 8 and including end loops and end cross bars, and two inner curved members formed of continuations of said loops and arranged to snugly engage and cross each other and a finger piece hingedly connected to one of said cross bars.

2. A fastening clip for use upon belts and the like, comprising a wire bent into substantially the form of a figure 8 and including end portions and two inner curved members formed of the wire of said loops and arranged to snugly engage and cross each other at one or more places, and a finger piece pivotally connected to one bar of one of said portions.

3. A fastening clip for use upon belts and

the like, comprising two wire members pivotally connected together, and each bent to form substantially a figure 8 and including two outer bar portions, each terminating in loop end portions and two intermediate members formed of a continuation of said loops and arranged to snugly engage and cross each other.

4. A fastening clip for use upon belts and the like, comprising a single piece of wire bent into substantially the form of a figure 8 and including two end loops, having straight outer crossed bars and an intermediate portion disposed to engagingly cross each other at two or more places to frictionally hold a web when threaded therebetween.

5. A fastening clip for use upon belts and the like, comprising a single piece of wire bent to form loop end portions, having straight outer cross bars connecting said loops and having two inner crossed curved members disposed one against the other at the center and adjacent the two looped end portions to frictionally hold a web when threaded therebetween.

6. A fastening clip for use upon belts and the like, comprising a wire bent to form two outer loops, each having a straight outer cross bar and connecting intermediate portions crossing each other at two or more spaced apart positions and yieldably disposed one against the other and forming relatively small intermediate loops.

Signed at Bridgeport in the county of Fairfield and State of Connecticut this 7th day of October A. D. 1926.

CLARENCE MURPHY.
